UNITED STATES PATENT OFFICE.

WEBSTER C. ESTES, OF FLATBUSH, NEW YORK.

DESIGN FOR A BOX.

SPECIFICATION forming part of Design No. 21,762, dated August 9, 1892.

Application filed June 27, 1892. Serial No. 438,212. Term of patent 7 years.

To all whom it may concern:

Be it known that I, WEBSTER C. ESTES, a citizen of the United States, residing at Flatbush, in the county of Kings and State of New York, have invented a Design for a Box, of which the following is a specification.

The leading feature of this design for a box is the ornamental configuration of the top and edges, such design consisting in an oblong ¹⁰ raised panel with a beveled border that is rounded at the junction of its edges with the sides and end of the case.

This design is represented in Figure 1 by a plan view, and in Fig. 2 by an elevation.

The box is oblong with rounding corners at ¹⁵ 2, and the raised panel 3 on the top is oblong, and the border around the same is beveled downwardly, as at 4, with rounding edges 5 at the junction with the sides and ends.

I claim--

The design for a box, substantially as described and represented.

Signed by me this 22d day of June, 1892.

WEBSTER C. ESTES.
